INSULATED TERMINAL CONNECTOR

Harry J. Holmes, Basking Ridge, N.J., assignor to The Thomas & Betts Co., Elizabeth, N.J., a corporation of New Jersey

Application April 23, 1959, Serial No. 55,632

Term of patent 14 years

(Cl. D26—1)

Fig. 1 is a perspective view of an insulated terminal connector showing my new design;

Fig. 2 is a top plan view;

Fig. 3 is a front elevational view; and

Fig. 4 is a side elevational view thereof, partially broken away and in cross-section.

A portion of the drawing figures is diagonally lined to indicate transparency.

I claim:

The ornamental design for an insulated terminal connector, as shown and described.
